UNITED STATES PATENT OFFICE.

JAMES G. FAIRBANKS, OF MARION, OHIO.

EXCAVATOR.

No. 892,508.

Specification of Letters Patent.

Patented July 7, 1908.

Application filed January 2, 1908. Serial No. 408,969.

To all whom it may concern:

Be it known that I, JAMES G. FAIRBANKS, a citizen of the United States, residing at Marion, in the county of Marion and State of

5 Ohio, have invented a new and useful Excavator, of which the following is a specification.

This invention relates to excavating apparatus employed for ditching and other purposes, and has for its principal object to provide a novel form of bucket and bucket supporting actuating means in which the bucket may be completely filled, swung to any desired point, and the entire contents dis- 10 charged without regard to the condition of the load, the apparatus being equally effective in digging dry or wet material.

A further object of the invention is to provide a scraper bucket having a stiff or rigid handle which may be locked in any position of adjustment so as to hold the bucket down to its work, and which will further permit ready movement of the bucket to and from loading and discharging positions.

25 A still further object of the invention is to provide a drag cable machine in which the strain on the boom is materially reduced, the work of the boom being practically limited to the movement of the bucket and its carrying handle between loading and discharging positions.

A still further object of the invention is to provide a drag line machine of this class in which the bucket and its handle are adjust- 30 ably connected for the purpose of securing a greater or less rake or clearance of the bucket while in use.

With these and other objects in view, as will more fully hereinafter appear, the invention 40 consists in certain novel features of construction and arrangement of parts, hereinafter fully described, illustrated in the accompanying drawings, and particularly pointed out in the appended claims, it being understood that various changes in the form, proportions, size and minor details of the structure may be made without departing from the spirit or sacrificing any of the advantages of the invention.

50 In the accompanying drawings:—Figure 1 is an elevation of a ditching machine constructed in accordance with the invention, the engine and portions of the operating mechanism being omitted. Fig. 2 is a detail perspective view of the excavating bucket and its handle. Fig. 3 is a sectional

plan view on an enlarged scale on the cable 3—3 of Fig. 1. Fig. 4 is a sectional elevation showing the bucket in load discharging position.

Similar numerals of reference are employed to indicate corresponding parts throughout the several figures of the drawings.

In the drawing, 10 designates the main body or frame of the excavating machine, and this portion of the device may be of any construction and arranged for operation on dry land, or it may be in the form of a scow or flat boat for ditching or dredging operations.

At the front portion of the frame 10 is mounted a derrick frame 11, and in front of the frame is a turn table 12, on which is mounted the foot of a boom 15 of any desired length. The top of the boom is secured to the top of the derrick by a tension member 16, and the derrick has a tension brace 17, all of these parts being arranged in the ordinary manner.

At the outer end of the boom is a shaft 20 on which is mounted a sheave 21, and over this sheave passes a hoisting cable 22, the lower end of which is connected to the bucket, while the inner end of the cable passes to a suitable winding drum 23. To the opposite end portions of the shaft is pivoted a yoke 24, that serves as a guide for a bucket handle 25, said handle being formed of two parallel bars 27 that are spaced from each other to permit the passage of the sheave 21 between them, so that the sheave and the yoke coact to guide said handle and preserve the same in proper relative position to the boom.

Mounted loosely on the shaft 20 are two small sheaves 28 and 29 which are free to revolve independently of each other and independently of the sheave 21. These small sheaves are grooved and their extreme peripheral portions serve as roller bearings for engagement with the inner face of the handle 25. Secured to a bracket 30 at the lower end of the handle is a cable 31 that passes up over the sheave 28, and thence follows down the line of the boom to a grooved drum 33 that is rigidly secured to a shaft 34 mounted in bearings near the lower end of the boom, the cable being wound around the drum and its end being rigidly secured thereto. Secured to a bracket 36 at the top of the handle is a cable 37 that passes under the sheave 29, and thence over a sheave 38 passing down

the boom, and being wound around the drum 33 in a direction opposite to that in which the cable 31 is wound. The end of the cable 37 is, also, connected to this drum.

5 At the end of the drum is a friction disk 40, that is surrounded by a band brake 41 having one end secured to a bracket 42 on the boom, and its opposite end being connected to one arm of the lever 43, the opposite arm 10 of said lever being connected through a bell crank lever 44 to an operating rod 45 that is arranged within convenient reach of the attendant on the machine, so that by pulling downward on the rope, the friction drum may 15 be held, and the cables prevented from winding or unwinding so that the handle will be positively locked in any position to which it may have been adjusted. When it is desired to raise the handle or lower the same, the 20 braking device is released and the drum is turned in one or other direction to unwind one of the cables and wind up on the other.

Secured rigidly to the lower end of the handle 25 is a yoke 47 that straddles the 25 bucket 48, and is pivotally connected to pins 49 projecting from the opposite sides thereof, said pins being disposed in the vertical plane of the center of gravity of the bucket and preferably at a point below such center of 30 gravity, so that the turning of the bucket to dumping position is facilitated.

To the upper portion of the front of the bucket is secured a yoke 50, the upper central portion of which is connected to the 35 lower end of the hoisting cable 22, this cable serving as a means of raising the bucket and its handle. In order to prevent over turning of the bucket by the operation of the hoisting cable, the rear end of the bucket is 40 connected to a hook 52 mounted on the handle by means of a chain 53, and this chain may be hooked up in order to vary the angular position or rake of the bucket as may be demanded by the character of the material 45 being excavated.

Pivoted to the forward end of the bucket is a bail 55, from which leads a filling rope 56 to any suitable hoisting means.

In operation, the bucket is lowered to the 50 digging position by slackening the hoisting cable 22, and at the same time loosening the brake 41. The bucket and its handle will descend by gravity and the cable 31 in unwinding from the drum 33 will turn said drum, so 55 as to wind up on the cable 37, so that these two cables will remain taut. When the bucket has reached the digging position, the brake is applied, and the bucket is thus held down firmly in place. The filling rope 56 is 60 then wound up hauling the bucket in the direction of the main frame and filling the same to the desired extent. The brake is then released and the hoisting rope 22 is wound up, elevating the handle and the 65 bucket, after which the boom is swung to

dumping position, the brake being first applied to hold the handle and bucket in the new position. When the dumping position is reached, the filling cable is slackened and the forward end of the bucket tilts downward, 70 the bucket being practically inverted and dumping its entire contents.

I claim:—

1. In a drag cable excavating machine, a boom, a bucket, a rigid bucket handle connected pivotally to the bucket and having a 75 slideable connection with the boom, a pair of cables connected one to the upper and the other to the lower end of the handle, a drum around which said cables pass in opposite directions, respectively, means for controlling the rotative movement of said drum, and a filling line connected to the bucket.

2. In an excavating machine, a boom, a bucket, a rigid handle pivotally connected to 85 the bucket, and slidably connected to the boom, a pair of sheaves carried by the boom and in part guiding the handle, a pair of cables connected one to the lower end and the other to the upper end of the boom and extending around said sheaves, a drum around 90 which said cables pass in opposite directions, respectively, a friction braking mechanism for controlling the rotative movement of the drum, and a filling line connected to the 95 bucket.

3. In an excavating machine, a boom, a bucket, a rigid handle pivotally connected to the bucket, a shaft carried by the boom, a central sheave, and a pair of side sheaves 100 mounted on the shaft and arranged for independent rotative movement, the handle having a central space for the passage of said central sheave, and the peripheries of said sheaves being arranged to engage against the 105 inner face of said handle, a yoke pivoted on the shaft and embracing said handle, a pair of cables connected one to the upper and the other to the lower end of the handle and extending around said side sheaves, a drum 110 carried by the boom and around which the cables pass in opposite directions, respectively, a friction brake controlling the rotative movement of the drum, a hoisting cable passing over the central sheave and arranged 115 to elevate the bucket, and handle, and a filling line connected to said bucket.

4. In an excavating machine, a boom, a bucket, a rigid handle, a yoke carried by the handle and straddling the bucket, the yoke 120 being pivotally connected to the bucket at a point adjacent to the vertical plane of and below the center of gravity of the bucket, a hoisting cable connected to the forward end of the bucket and limiting means connecting 125 the rear end of the bucket to the handle, and a filling line connected to said bucket.

5. In an excavating machine of the class described, a bucket, a rigid handle pivotally connected thereto, a hoisting rope connected 130

to the forward portion of the bucket, and an adjustable connection between the rear end of the bucket and the handle to thereby permit alteration of the rake of the bucket.

5 6. In a drag line excavating machine a boom, a bucket, a handle connected to the boom and pivotally connected to the bucket at a point which is lower than the center of gravity of the bucket when in loading position, means for locking the handle in adjusted position and a filling line connected to said bucket.

10 7. In a drag line excavating machine, a boom, a bucket, a handle connected to the boom and pivotally connected to the bucket at a point which is lower than the center of gravity of the bucket when in loading position and which is in the same vertical plane with the center of gravity of the bucket when 20 in dumping position, means for locking the handle in adjusted position, and a filling line connected to said bucket.

15 8. In an excavating machine a handle, a yoke having spaced upper portions attached to opposite sides of the handle, the said portions converging toward each other at their 25 ends and merging at their extremities, the converging portions of the yoke depending at an angle to the intermediate portion thereof

and a bucket pivotally mounted between 30 the said depending end portions of the yoke.

9. In an excavating machine, a handle, a bucket pivotally connected with the handle, a flexible member connected with the handle and bucket and adapted to limit the swing of 35 the bucket and a filling line connected with the bucket.

10. In an excavating machine, a handle, a bucket pivotally connected with the handle, and a filling line connected with the bucket 40 and adapted to hold the same in loading position when taut and permit the bucket to swing into dumping position when slack.

11. In a drag line excavating machine, a boom, a bucket, a handle connected to the 45 boom and pivotally connected to the bucket, a flexible member connected with the handle and bucket for limiting the swing of the bucket, means for locking the handle in adjusted position, and a filling line connected to 50 said bucket.

In testimony that I claim the foregoing as my own, I have hereto affixed my signature in the presence of two witnesses.
